UNITED STATES PATENT OFFICE.

FRANKLIN CHATFIELD, OF MINNEAPOLIS, MINNESOTA, AND GEORGE E. RUTLEDGE, OF ROCHELLE, ILLINOIS, ASSIGNEES OF ONE-HALF TO NORTHWESTERN KNITTING CO., OF MINNEAPOLIS, MINNESOTA, A CORPORATION, AND ONE-HALF TO VASSAR SWISS UNDERWEAR CO., OF ROCHELLE, ILLINOIS, A CORPORATION.

UNDERGARMENT.

1,196,431.

Specification of Letters Patent. Patented Aug. 29, 1916.

Application filed October 8, 1912. Serial No. 724,604.

To all whom it may concern:

Be it known that we, FRANKLIN CHATFIELD, of Minneapolis, Hennepin county, Minnesota, and GEORGE E. RUTLEDGE, of 5 Rochelle, Ogle county, Illinois, have invented certain new and useful Improvements in Undergarments, of which the following is a specification.

Our invention relates to union suit undergarments and the object of the invention is 10 to provide a garment with a permanently closed crotch and a wide or full posterior opening in which there will be no gaps or exposed openings when the garment is in 15 use.

A further object is to provide a union undergarment having a permanently closed crotch seat portion from which all straight 20 seams are eliminated, and a garment having no seams in the crotch or seat portion to annoy or chafe the wearer.

A further object is to provide a garment in which there will be no overlapping of 25 the fabric in the crotch and the consequent bunching of the garment in the seat or crotch portion.

Other objects of the invention will appear from the following detailed description.

The invention consists generally in the 30 garment as hereinafter described and particularly pointed out in the claims.

In the accompanying drawings forming part of this specification, Figure 1 is a rear view of the garment as it will appear on the 35 wearer, Fig. 2 is a detail view of a portion of the fabric, showing a section cut therefrom to provide for a wide or full posterior opening, Fig. 3 is a detail view of the section, the upper portion of which closes the 40 posterior opening and the lower portion forms the leg gores, Fig. 4 is a detail view showing the gore and flap section in the completed garment, and the buttons for holding the flap in place over the opening, 45 Fig. 5 is a detail view looking at the front of the garment, showing the position of the gores and the location of the seams with respect to the crotch.

In the drawing, 2 represents a section of 50 fabric from which the undergarment is

formed. This fabric may be in the form of a tube or knit flat in two parts and stitched together, as preferred. We do not confine ourselves to the application of the invention to any particular form or weave of the fabric. When applied to a garment made from a fabric tube, we prefer to cut the tube lengthwise, as at 3, to form the leg portions of the garment, and provide for the insertion of the gore in the seat and crotch. In 55 the preferred construction and in a garment made from tubing, we remove a section, preferably triangular, leaving a wide posterior opening 4. This opening has a substantially straight upper edge extending 60 preferably across the back portion of the garment with downwardly converging edges 6 which preferably intersect the edges of the leg portions of the garment formed by the longitudinal slit 3. To cover this opening we provide a fabric section 7, the lower 65 portions of which are preferably stitched to the edges 6 and form the leg gores, increasing the fullness of the leg portions at the crotch. The edge 5 of the opening 4 is 70 75 preferably located opposite, approximately, the lower end of the opening 8 at the front of the garment, and the gore section 7, as shown plainly in Fig. 4, provides sufficient looseness or slack to allow for the separation of the sides of the fabric to expose the posterior opening. The lower portions of the gore will extend under the crotch to the front of the garment. There will be no 80 gaps, either in the crotch or in the front or rear, and the seams are so located that the back portion of the garment will be elastic and all danger of chafing the wearer by cross seams or seams in the crotch and seat will be entirely eliminated. Furthermore, 85 there will be no lapping of the fabric in the crotch to cause discomfort to the wearer. The upper portion of the gore section forms a loose drop section or flap 9 which covers the upper portion of the posterior opening 90 and is provided with button-holes 10 therein to engage buttons 11 secured to the back of the garment above the opening 4. We have shown two of these buttons, but do not limit ourselves to this number, as a 95 100

greater or less number may be employed, if preferred. The buttons are easily accessible to the wearer of the garment, and when the flap is disengaged from the buttons or other fastening means which may be provided, it will drop down and expose the posterior opening of the garment without the necessity of opening the front portion thereof, and when the flap is released the crotch and seat may be entirely opened.

At the points where the gore flap is secured to the body portion of the garment a reinforcing tape 12 may be used which will reinforce the fabric at these points of strain when the gore flap is opened.

We claim as our invention:—

1. A union garment having a posterior opening formed by cutting out a substantially triangular section of the fabric from 20 which the garment is made, the upper edge of said opening extending across the garment from side to side thereof, and the side edges of said opening converging to a point below the crotch of the garment, a seat 25 section stitched to the side edges of said opening and forming gore portions extending into the legs of the garment below the crotch thereof, said gore portions also extending to the front of the garment and 30 stitched thereto and forming a permanently closed seamless crotch, the upper portion of said seat section forming a loose drop flap for covering said opening, and means for connecting said flap to the back of the garment.

2. A union garment having a posterior opening formed by cutting out a triangular section of the fabric from which the garment is made, the upper edge of said opening being substantially straight and extending 40 across the garment from side to side thereof, and the side edges of said opening converging to a point below the crotch of the garment, a seat section stitched to the 45 side edges of said opening and forming gore portions extending into the legs of the garment below the crotch thereof, said gore portions also extending to the front of the garment and stitched thereto and forming a 50 permanently closed seamless crotch, the upper portion of said seat section forming a

loose drop flap for covering said opening, and means for connecting said flap to the back of the garment, the lines of stitching for securing the seat section to the side 55 edges of said opening being extended to points above the extremities of the upper edge of said opening.

3. A union garment having a posterior opening formed by cutting out a triangular section of the fabric from which the garment is made, the upper edge of said opening being substantially straight and extending across the garment from side to side thereof, and the side edges of said opening converging 65 to a point below the crotch of the garment, a seat section stitched to the side edges of said opening and forming gore portions extending into the legs of the garment below the crotch thereof, said gore portions also 70 extending to the front of the garment and stitched thereto and forming a permanently closed seamless crotch, the upper portion of said seat section forming a loose drop flap for covering said opening, and means for connecting said flap to the back of the garment, the lines of stitching for securing the seat section to the side edges of said opening being extended to points above the extremities of the upper edge of said opening, and 75 tapes secured to the back of the garment and to said flap at the ends of the lines of stitching for reinforcing the same.

In witness whereof, we have hereunto set our hands to the specification for which we have made petition for Letters Patent of the United States September 27th, 1912, and October 2nd, 1912, filed October 8, 1912, Serial No. 724,604, Franklin Chatfield at Minneapolis, Hennepin county, Minnesota, 90 this 30th day of June, 1913, and George E. Rutledge at Rochelle, Ogle county, Illinois, this 3rd day of July, 1913.

FRANKLIN CHATFIELD.
